CLAIM

The ornamental design for a label printer, as shown and described.

DESCRIPTION

FIG. 1 is a perspective view of the invention showing my new design;

FIG. 2 is a top view thereof;

FIG. 3 is a bottom view thereof;

FIG. 4 is a right side thereof;

FIG. 5 is a left side thereof;

FIG. 6 is a front side view thereof;

FIG. 7 is a rear side view thereof;

FIG. 8 is a perspective view of the invention of FIG. 1 with the cover in an open position;

FIG. 9 is a top view of the invention of FIG. 8;

FIG. 10 is a bottom view of the invention of FIG. 8;

FIG. 11 is a right side view of the invention of FIG. 8;

FIG. 12 is a left side view of the invention of FIG. 8;

FIG. 13 is a front view of the invention of FIG. 8; and,

FIG. 14 is a rear view of the invention of FIG. 8.
